Primary Examiner — Cathron Brooks(74) Attorney, Agent, or Firm — Kolisch Hartwell, P.C.(57) CLAIM

The ornamental design for a bassinet, as shown and described.

DESCRIPTION

FIG. 1 is perspective view of a bassinet showing the new design;

FIG. 2 is a left side view thereof;

FIG. 3 is front view thereof;

FIG. 4 is a right side view thereof;

FIG. 5 is a rear view thereof;

FIG. 6 is a top view thereof; and,

FIG. 7 is a bottom view thereof.

The broken lines illustrate portions of the bassinet that form no part of the claimed design.

1 Claim, 4 Drawing Sheets(56)
